CLAIM

The ornamental design for a automatic teller machine kiosk, substantially as shown and described.

DESCRIPTION

FIG. 1 is a left front perspective view of the automatic teller machine kiosk showing my new design;

FIG. 2 is a right front perspective view thereof;

FIG. 3 is a front elevational view thereof;

FIG. 4 is a rear elevational view thereof; and,

FIG. 5 is a left side elevational view, the undisclosed right side being a mirror image view of the left side.
